TOILET TANK BALCOCK

Charley L. Goldtrap, Evergreen, Colo., assignor to Twentieth Century Products Corporation, Denver, Colo.

Filed Oct. 16, 1961, Ser. No. 67,109

Term of patent 14 years

(Cl. D91—3)

FIG. 1 is a side elevational view of a toilet tank ballcock, showing my new design therefor;
FIG. 2 is a top plan view thereof; and
FIG. 3 is a bottom plan view thereof.

The broken line representations are for illustrative purposes only.

The side of the toilet tank ballcock not shown is substantially the same in appearance as the side shown.

This application is a continuation-in-part of my pending application D-64,148 filed March 6, 1961, for a toilet tank ballcock and now abandoned.

I claim:

The ornamental design for a toilet tank ballcock, substantially as shown and described.
